ADJUSTABLE TABLE ATTACHMENT

Filed Jan. 27, 1950

UNITED STATES PATENT OFFICE

2,580,144

ADJUSTABLE TABLE ATTACHMENT

Stanley F. Webster, Nashville, Tenn.

Application January 27, 1950, Serial No. 140,849

4 Claims. (Cl. 311—103)

1

This invention relates to a novel attachment for tables primarily adaptable to dining tables to provide an auxiliary table or tray which is supported solely by the dining table and beneath the level of the top surface thereof and which is primarily adaptable for use as a dining tray for a child to replace the conventional high chair and to enable a child to be conveniently fed with the parents or adults at a dining table and while seated on a conventional chair.

Another object of the device is to provide a table attachment which will enable a child to be placed at the parents' dining table at an early age as recommended by child psychologists and which is so disposed that the parent can very conveniently feed a child while seated at the table or assist the child in feeding itself.

Still a further object of the invention is to provide a table attachment which may be readily removed from or applied to a table and which may be very conveniently stored or carried, as while traveling, to afford a means for conveniently feeding a child at a restaurant or elsewhere.

Still another object of the invention is to provide a table attachment which may be left in place on a dining table and which is adjustable for positioning the attachment completely beneath the table when not in use.

Still a further object of the invention is to provide a table attachment which may be additionally used as an auxiliary supporting surface to a dining table for supporting hot dishes or other articles which might injure the finish of the table surface and which may be utilized in connection with other types of tables, as for supporting a typewriter.

Various other objects and advantages of the invention will hereinafter become more fully apparent from the following description of the drawing, illustrating a presently preferred embodiment thereof, and wherein:

Figure 1 is a side elevational view, partly in vertical section showing the invention in an applied, operative position;

Figure 2 is a top plan view thereof, partly broken away and partly in section;

Figure 3 is an elevational view, partly in section taken along a plane as indicated by the line 3—3 of Figure 1;

Figure 4 is a fragmentary horizontal sectional view taken substantially along a plane as indicated by the line 4—4 of Figure 3, and

Figure 5 is a vertical sectional view taken substantially along a plane as indicated by the line 5—5 of Figure 3.

2

Referring more specifically to the drawing, the table attachment in its entirety is designated generally 6 and includes a clamp, designated generally 7 which comprises a body member 8 and two clamping screws 9. The body member 8 includes a top wall 10, a bottom wall 11 and a side wall 12 which extends between complementary edges of the top and bottom walls and which is formed integral therewith. The top wall 10 is adapted to rest upon the upper surface of a portion of a table 13, such as a conventional dining table and the side wall 12 is adapted to be disposed against a portion of the edge of the table 13 and said walls 10 and 12 are lined on their inner sides with felt or rubber pads 12a to prevent damage to the table finish. The top and bottom walls 10 and 11 are spaced a sufficient distance apart so that the bottom wall 11 will be spaced from the under surface of the table 13. The clamping screws 9 extend upwardly through threaded openings 14 in the bottom 11 and are provided on their upper ends with removable pads 15 for engaging the underside of the table top 13 without marring or damaging the finish thereof. The lower ends of the clamp screws 9 are preferably provided with wing shaped heads 16 to enable said clamping screws to be readily tightened with the fingers for detachably securing the clamp 7 rigidly to the table top 13, as illustrated in Figures 1 and 3.

30 A hanger post 16 has an upper restricted end 17 which extends through an opening 18 in the bottom 11 of the clamp 7 and the upper end of said restricted portion 17 is flattened to form a head 19 which engages the upper side of the bottom 11 for clamping the post 16 thereto. The post 16 depends perpendicularly from the bottom 11 and is provided with two rows of diametrically opposed threaded recesses 20, the recesses of each of which rows are longitudinally spaced. 35 The hanger post 16 may be provided with a detachable extension 21 likewise provided with corresponding threaded recesses 20 and which has a threaded shank 22 projecting from its upper end for detachably engaging in a downwardly opening threaded recess 23 in the lower end of the post 16, as best illustrated in Figure 1.

40 A tray, designated generally 24 has a back portion 25 which is provided, intermediate of its side edges 26 with an opening 27 to loosely engage the post 16 or its extension 21. A collar 28 is disposed above the tray portion 25 and has a flange 29 resting thereon and secured thereto by fastenings 30. A second, preferably longer collar 31 is disposed beneath the tray portion 25 and has a larger flange 32 disposed against the

underside thereof and secured thereto by additional fastenings 30. The bores of the collars 28 and 31 register with the opening 27. The collar 31 is provided with a radial threaded bore 33, as seen in Figure 1, of the same diameter as the threaded recesses 20 and which may register with any one of said recesses and through which extends a locking screw 34 having a wing-shaped head 35, which is adapted to be threadedly advanced through the opening 33 into engagement with one of the recesses 20 for supporting the tray 24 at any desired level on the hanger posts 16 or 21 and below the level of the table top 13. The locking screw 34 preferably has a flange 36 which is adapted to be advanced into engagement with the collar 31 for displacing said collar radially into clamping engagement with the post 16. The forward portion of the tray or supporting surface 24 is provided with a recess 37 in its upper side which is adapted to retain dishes or other articles upon the tray 24.

A bar 38 is secured by fastenings 39 to each side edge 26 of the tray and said bars 38 are of a width greater than the thickness of the tray to project above and beneath the top and bottom surfaces, respectively thereof, as seen in Figure 5. Each side edge of the tray 24 is provided with an arm rest 40 which is provided with a groove 41 of T-shaped cross section which opens inwardly thereof and which preferably extends from end-to-end of the arm rest 40. The groove 41 is adapted to slidably receive one of the bars 38 and the edge portion 26 of the tray 24, as illustrated in Figure 5 for slidably mounting said arm rests on the side edges 26 of the tray. The inner or rear end of each arm rest 40 is provided with a recess 42 one end of which opens into a portion of the groove 41 for receiving a headed retaining pin 43, the shank of which extends through said recessed end, into the groove 41 to detachably engage in a recess 44 formed in the bar 38 and the complementary tray edge 26. Each bar 38 and complementary tray edge 26 is provided with one recess 44, adjacent the rear end of the bar 38 and two, spaced recesses 44, located near the opposite, forward end of said bar 38. A leaf spring 45 is suitably secured at one of its ends to the intermediate portion of the retaining pin shank and projects transversely therefrom and longitudinally of the recess 42 and has its opposite end seated in an undercut recess 46 of the arm rest 40 and secured therein by a fastening 47. The retaining pins 43 are urged inwardly of the tray 24 by the leaf springs 45 and may be manually retracted outwardly for disengaging them from selected recesses 44 so that the arm rest 40 may be latched in a fully retracted position, as illustrated at the left of Figure 2 or in either of two projected positions as illustrated at the right of Figure 2.

It will be readily apparent that when the tray 24 is disposed as illustrated in Figures 2 and 3 that a child, for example, may sit comfortably upon a conventional chair and eat from the tray 24 which may be adjusted vertically on the hanger post 16, as previously described, for positioning the tray 24 at a convenient level for the

child, and the arm rest 40 may be extended, as illustrated at the right of Figure 2, to prevent the child from falling from the chair and to provide supports for the arms. When the table attachment 6 is not in use it may be completely removed from the table top 13 by loosening the clamping screws 9 for storage or transportation or by loosening the screw 35 to disengage it from the recesses 20, the tray 24 may be revolved about the post 16 through an arc of 180° for positioning the tray completely beneath the table top 13 and the screw 35 may then be advanced into a recess 20 in the diametrically opposite side of the post 16 for thus supporting the tray in an inoperative position and beneath the table top.

Various modifications and changes are contemplated and may obviously be resorted to, without departing from the spirit or scope of the invention as hereinafter defined by the appended claims.

I claim as my invention:

1. An attachment for horizontal supporting surfaces such as table tops comprising a clamp adapted to be detachably secured to an edge portion of a table top and having a bottom portion disposed therebeneath, a hanger post connected to and depending from said bottom portion of the clamp and disposed beneath the table top and substantially perpendicular thereto, a tray slidably supported on said hanger post in a plane substantially parallel to the plane of said table top, and means for adjustably securing the tray to the hanger post for supporting the tray at different levels below said supporting surface in either an inoperative position completely beneath the table top or in an operative position projecting outwardly from an edge of the table top.

2. An attachment as in claim 1, said tray having a forward portion and a rear portion, said rear portion being disposed beneath said table top and being provided with an opening through which the hanger post loosely extends.

3. An attachment as in claim 1, arm rests adjustably connected to corresponding side edges of said tray for movement to extended positions beyond an outer, forward edge of the tray.

4. An attachment as in claim 1, arm rests slidably connected to corresponding side edges of said tray for movement to extended positions beyond an outer, forward edge of the tray, and latch means carried by said arm rests for releasably latching the arm rests in retracted positions or in a plurality of extended positions.
